[57] CLAIM

The ornamental design for a power switch for video camera with video tape recorder, as shown and described.

DESCRIPTION

FIG. 1 is a front view of a power switch for video camera with video tape recorder showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof as viewed from the right and front direction.

The broken line shown in all views are for illustrative purposes only and form no part of the claimed design.

1 Claim, 5 Drawing Sheets
